DEFROSTING ARRANGEMENT

Carlyle M. Ashley, Syracuse, N. Y., assignor to
 Carrier Corporation, Syracuse, N. Y., a corporation of Delaware

Application May 20, 1943, Serial No. 487,746

8 Claims. (Cl. 62—1)

This invention relates to defrosting by the use of water and more particularly to refrigeration and other systems wherein it is desired to remove accumulations of ice and frost from a series of coils.

A feature of the invention resides in the provision of a series of channels in a top or cover plate of an evaporator casing or the like. A water coil positioned within each channel directs a flow of water for defrosting against the body of the channel. The water then flows toward and down the legs of the channel, dropping upon the coils to be defrosted, which are positioned below and in vertical alignment with the legs.

A further feature resides in providing for drainage by gravity from the water coils. Since the coils have their discharge openings at the top, drainage by gravity will leave a space in the coils at the top, even though gravity drainage is incomplete. Consequently, when the flow of water for defrosting is resumed, sufficient water will be circulated in such space to assure resumption of defrosting operations, and to clean out such ice as may have formed because not all of the water had been drained at the conclusion of the previous defrosting operation.

These and other features and advantages will be more apparent from the following description of one form of the invention to be read in connection with accompanying drawings in which:

Fig. 1 is a diagrammatic view, in section, showing a series of coils adapted to be defrosted by a water defrosting arrangement in accordance with applicant's invention;

Fig. 2 is a detailed view of a channel member with a water coil positioned therein; and

Fig. 3 shows, diagrammatically, a piping arrangement adapted to serve the channels used for directing the water for defrosting.

Considering the drawings, similar designations referring to similar parts, numeral 4 represents the casing of a unit, such as a cold diffuser unit, or other apparatus employed for refrigeration purposes. In such units, it is usual to provide a series of coils 5, through which refrigerant or cold brine is circulated. A fan is normally employed with many such units for circulating air over the cold coils. The temperature of coils 5 is often below the freezing point, with the result that ice or frost will accumulate upon the coils, as is well known in the art.

Since the efficiency of the system in which such units may be employed is impaired when the accumulations of frost become excessive, it is necessary to remove the frost periodically. This

may be done by cutting out the refrigeration system serving coils 5, assuming a direct expansion system is used, or where brine is circulated, the circulation may be stopped. Such shut-down is undesirable, since the temperature in the area served by the coils will undesirably rise. Therefore, it has been the aim of those skilled in the art to provide a system for defrosting speedily. Such attempts as have been made for defrosting by use of water have provided expensive valve and vent arrangements, as well as complications in operation. Applicant's simple arrangement avoids such devices and eliminates substantially the use of methods of operation which are subject to failure.

Since the use of a fan, refrigerant feed arrangement for coils 5, and details of the casing 4, form no part of the invention, they are not identified, and the description is confined to the defrosting arrangement per se.

Coils 5 may be arranged in any number of rows, depending upon the capacity of the system and other characteristics thereof. As illustrated, six vertical rows numbered 6, 7, 8, 9, 10, and 11 are shown. These may be in casings, or otherwise positioned within 4.

Channels 12 are suitably affixed to cover plate 13 arranged to fit over casing 4, in watertight manner. A water defrosting coil or pipe 14 is positioned within each channel 12. At the top of each pipe 14 is provided a series of water discharge openings 15. As shown in Fig. 2, the openings may be in the form of small holes, or shaped as desired, through which water from pipes 14 is discharged upwardly against the inner surface of the top or channel portion of 12, spaced preferably not more than an inch above the pipes. Each channel has a center channel portion 16 and two legs 17, as shown in Fig. 2. The water discharged from pipes 14 upwardly against center portion 16 mushrooms in a plurality of directions, spreading longitudinally as well as transversely, and impinging against both legs 17, to form continuous vertical sheets dropping from the legs.

The coils to be defrosted, 5, are positioned in line with legs 17. A sufficient flow of water is provided over the frosted surfaces of coils 5 so that the surfaces will be raised in temperature and the frost rapidly melted away.

As shown in Fig. 3 pipes 14 may be provided in parallel or, as shown, in series, served by water from a suitable source of supply leading in through line 18. A valve 19 controls the admission of the water. A union 20 is provided for coupling pipes 14 to the water line. The pipe coil 14 is

dead ended so that a maximum pressure of discharge through orifices 15 will result upon opening valve 19. Pipe coil 14 may be affixed to the inside of the cover plate 13 as by brackets 22, and spaced therefrom so that the pipes may depend as illustrated, below the channel members

Pipes 14 have one or more drainage openings 23 at the bottom, so that when valve 19 is closed and the supply of water shut off, drainage of such water as remains in the pipes will take place, at least in appreciable part, through drainage openings 23.

In Fig. 2 a dash dot line is shown within pipe 14. This is intended to illustrate a condition where subsequent to a frosting operation, pipes 14 have drained only partially. The result is that residue of water in the bottom of pipes 14 is shown frozen, as would take place during refrigeration periods between the times when defrosting takes place. However, when defrosting is desired, and valve 19 opened, the surge of water in the open space above the ice, within pipes 14, will be sufficient to carry on the defrosting operation. The water will be discharged through openings 15 upwardly and then flow down the legs 17, dropping upon the accumulations on coils 5. Since the water is much higher in temperature than the ice in pipes 14, it will soon cause the ice to be melted away, thus freeing the whole interior area of the pipes for flow of water. The drainage openings 23 will also be cleared so that at the conclusion of the defrosting operation they will be free to discharge water by gravity from the pipes, as aforesaid.

Since various changes may be made without departing from the scope of the invention, it is intended that all matter set forth in the description, or shown in the drawings be regarded as illustrative only and not in a limiting sense.

I claim:

1. A method of defrosting coils by the use of water and effecting drainage of water subsequent to defrosting consisting in supplying water upwardly against flow directing members positioned above the coils, repelling water from the members upon coils to be defrosted, and draining water from the source of supply utilized for the upward discharge, said water being drained by gravity.

2. In combination a casing, a plurality of refrigerated coils positioned within said casing, a top member in the casing, a plurality of channels integral with the top member, coils within the channels, means for discharging water from said last mentioned coils upwardly against the channels, said channels having legs positioned above the coils in the casing in such manner that water discharged upwardly in the channels will flow from the legs downwardly upon the coils in the casing, and means for draining the coils in the channels.

3. In combination, a casing, coils to be defrosted positioned within the casing, a plurality of inverted channels, said channels being positioned above said coils with the legs of said channels extending downwardly toward said coils, water circulating coils positioned to one side of the channels between the channels and the first mentioned coils, said water circulating coils having orifices in the upper side thereof for discharging water upwardly in the trough of the channels, and an orifice in the bottom of said water circulating coils for draining the coils, and means for supplying water to the water circulating coils, water dis-

charged upwardly from the coils into the channels flowing from the channels downwardly upon the coils in the casing to be defrosted.

4. In a combination of apparatus of the character described a casing, a top cover sheet for the casing, a plurality of channels integral with said sheet, a series of defrosting coils positioned within said channels, orifices in the upper sides of said coils facing said channels, an orifice in the lower side of said coils for enabling liquid in the coils to drain by gravity, each of said channels having a plurality of legs pointing downwardly, a plurality of coils adapted to be refrigerated positioned in said casing below and in vertical alignment with said legs, and means for supplying liquid to said defrosting coils.

5. A defrosting system of the character described for removing frost from a series of refrigerated coils, comprising a series of defrosting coils, means for supplying water to the defrosting coils, a plurality of channel members positioned above the defrosting coils, said members having a body portion and two legs, means for discharging water from the defrosting coils upwardly against the body portion, said water flowing downwardly from the legs, said refrigerated coils being positioned with respect to said legs so that water flowing from the legs will fall upon and wash away accumulations of frost from the refrigerated coils.

6. A method of defrosting refrigerated surfaces by the use of water and effecting drainage of water subsequent to defrosting, consisting in supplying water to a point of discharge, discharging said water at said point upwardly against a target, repelling water from the target upon the refrigerated surfaces whereby accumulations of frost will be removed from the surfaces, draining said water and melted frost by gravity from the area in which the refrigerated surfaces are located, discontinuing the supply of water to said point, and draining by gravity water remaining at said point of discharge after defrosting has been completed.

7. A method of supplying water for defrosting refrigerated surfaces and for draining water to prevent freezing at points of discharge of such water, consisting in supplying water to a tube having orifices at the top thereof, discharging water from the orifices against targets, repelling the water from the targets upon refrigerated surfaces to remove frost therefrom, draining by gravity the water and melted frost leaving the refrigerated surfaces, discontinuing the supply of the water to the tube, and draining the tube by gravity at least at one point thereof so that the water level in the tube will recede from the orifices and leave a space between the orifices and the level to which the water in the tube recedes.

8. A method of defrosting refrigerated surfaces by the use of water and draining such water without the use of a positive vent consisting in supplying water to a tube having a series of orifices above the center line of the tube, discharging water from the tube through said orifices against targets, repelling water from said targets upon a series of frosted coils, draining by gravity water and melted frost leaving the coils, discontinuing the supply of water to the tube and draining through orifices in the bottom of the tube such water as will escape by gravity whereby the water in the tube will recede to a level below the orifices.

CARLYLE M. ASHLEY.
